LATCHING MECHANISM

Gustaf Einar Lofgren, Riverside, and Clarence E. Stevens, Greenwich, Conn., assignors to Electrolux Corporation, New York, N. Y., a corporation of Delaware

Application January 23, 1941, Serial No. 375,610

5 Claims. (Cl. 292—51)

Our invention relates to latching mechanisms and more particularly to a latching mechanism operated by a single handle moving in a plane perpendicular to the latching mechanism.

An object of our invention is to provide an improved latching mechanism of the above type of simple construction which may be economically manufactured and assembled.

What we consider to be novel and our invention may be better understood by reference to the following specification and appended claims when considered in connection with the accompanying drawings, in which

Fig. 1 is a side view of a vacuum cleaner with the casing broken away in part;

Fig. 2 is an enlarged side sectional view of the front end of the vacuum cleaner;

Fig. 3 is an enlarged fragmentary front view of the vacuum cleaner with the front cover broken away, taken along the line 3—3 of Fig. 2;

Fig. 4 is an enlarged detail view of the keeper;

Fig. 5 is a partial view similar to Fig. 2 with the handle in a retracted position;

Fig. 6 is a partial view similar to Fig. 3 with the latching mechanism in a retracted position; and

Fig. 7 is a sectional view taken along the line 1—1 of Fig. 3.

Referring to the drawings, 10 indicates the casing of a vacuum cleaner of the type having an enclosed dust bag and pulled around on the floor by a flexible hose. A multi-stage centrifugal fan 11 driven by a motor 12 is mounted in casing 10. A dust bag 13 is mounted within casing 10 at the inlet end. Dust bag 13 is secured to a flanged ring 14 on which is located a rubber gasket 15. Gasket 15 is clamped against a ring 16 by a removable cover 17. A flexible hose 18 is secured in an inlet opening 19 in cover 17. A cleaning tool 20 is connected to the other end of hose 18 with a tubular handle member 21. Dust bag 13 may be removed from casing 10 for emptying by removing cover 17.

Cover 17 has a back plate 22 with a tubular sleeve 23 forming inlet opening 19 and secured thereto by a spun-over shoulder 24. Sleeve 23 has an inwardly extending flange 25 for cooperation with a connector 26 to secure hose 18 to cover 17. A stamping 27 is secured to plate 22 by means of screws 28 and has an opening 50 through which sleeve 23 extends. Stamping 27 is locked to plate 22 by the spun-over shoulder 24 on sleeve 23. A gasket 29 seals stamping 27 around sleeve 23. Similarly, a gasket 30 seals around sleeve 23. An operating handle 55

31 is pivotally mounted by a pin 32 on an upstanding central column 33 secured to a plate 48 which is riveted to back plate 22 by rivets 49. Handle 31 is movable in a plane perpendicular to plate 22 and in the direction in which cover 17 is moved to remove it from casing 10. Handle 31 is held in the opened or closed position by a spring 34 in the form of a flat strip which engages a transverse strap 35 and a pin 36 secured to column 33. Gear sectors 37 are secured to opposite sides of handle 31 and have outwardly extending teeth 38. Two gears 39 are secured to plate 48, one on each side of handle 31, and engage teeth 38. Two intermediate gears 40 are secured to plate 48 and mesh with gears 39. Two pivoted fingers 41 are adapted to enter bosses 42 to lock cover 17 to casing 10. Fingers 41 have integrally formed teeth 43 which engage intermediate gears 40. When handle 31 is in the position, indicated in Fig. 2, fingers 41 extend outwardly into engagement with springs 44 located within bosses 42. When handle 31 is moved to the retracted position shown in Fig. 5, fingers 41 are withdrawn from bosses 42 as shown in Fig. 6. As best indicated in Fig. 7, gears 39, intermediate gears 40, and fingers 41 are rotatably secured between a plate 45 and plate 48 by means of rivets 46. Bushings 47 are provided on rivets 46. The latching mechanism is assembled to plate 30 22 by securing handle 31 with spring 34 and gear sectors 37 to column 33 by pivot pin 32. Gears 39, intermediate gears 40, and fingers 41 with plates 45 are secured to plate 48 by rivets 46 and the latter plate is secured to the back plate 22 by rivets 49. After sleeve 23 is located in position, stamping 27 may then be secured to plate 22 by screws 28 and spun-over shoulder 24 to complete the assembly of cover 17. While a preferred form of the invention is 40 illustrated in the drawings, it should be understood that the invention is not limited to the details of construction, as shown, but the scope of invention is pointed out in the appended claims.

What we claim is:

1. A latching mechanism including a plate having a central upstanding column, a handle pivotally mounted on said column on an axis parallel to said plate, two gear sectors secured to said handle and rotatable therewith, two gears engaging said sectors and rotatably mounted on said plate on axes perpendicular to said plate, two intermediate gears rotatably mounted on said plate and meshing with said last-named gears, locking fingers pivotally mounted on said plate having gear teeth engaging said intermediate

gears, and a spring engaging said column and said handle.

2. A latching mechanism including a plate, a central upstanding column secured to said plate, a handle pivotally mounted on said column, a spring engaging said column and said handle, two gear sectors mounted on opposite sides of said column and secured to said handle for rotation therewith, gears mounted on said plate engaging said sectors, plates overlying said gears secured to said first-named plate, and locking fingers pivotally secured to said last-named plates and having gear teeth engaging said gears.

3. A latching mechanism including a plate, a handle pivotally mounted on said plate, a spring engaging said plate and said handle, two gear sectors secured to said handle for rotation therewith, gears mounted on said plate engaging said sectors, locking fingers pivotally secured to said plate and having gear teeth engaging said gears, and plates overlying said gears secured to said first-named plate and serving to secure said gears to said first-named plate.

4. A latching mechanism including a plate, a handle pivotally mounted for rotation in a plane

perpendicular to said plate, a gear sector secured to said handle for rotation therewith, a gear secured to said plate meshing with said gear sector, a second gear secured to said plate and engaging said first-mentioned gear, and a locking finger pivotally secured to said plate and having gear teeth engaging said second gear for pivotal movement from retracted to locked position upon movement of said handle.

5. A latching mechanism including a plate, a handle pivotally mounted for movement in a plane perpendicular to said plate, a gear sector secured to said handle for movement therewith, a gear mounted on said plate and engaging said

15 gear sector, an intermediate gear mounted on said plate and engaging said first-mentioned gear, a locking finger pivotally mounted on said plate and having gear teeth engaging said intermediate gear, and a plate overlying said gears and said

20 locking finger and secured to said plate by means serving also for rotatably securing said gears and said finger to said plate.

GUSTAF EINAR LOFGREN.
